J. A. DICKSON.

BACK OR LINING FOR FIREPLACES.

(Application filed Jan. 26, 1898.)

(No Model.)

Fig. 1.

UNITED STATES PATENT OFFICE.

JOHN ALBERT DICKSON, OF DEPORT, TEXAS.

BACK OR LINING FOR FIREPLACES.

SPECIFICATION forming part of Letters Patent No. 608,763, dated August 9, 1898.

Application filed January 26, 1898. Serial No. 668,035. (No model.)

To all whom it may concern:

Be it known that I, JOHN ALBERT DICKSON, a citizen of the United States, residing at Deport, in the county of Lamar and State of Texas, have invented a new and useful Back or Lining for Fireplaces, of which the following is a specification.

This invention relates to improvements in backs or linings for fireplaces of that class wherein the back is made in sections for application to and use in fireplaces of different sizes; and the object of the invention is to provide a simple and inexpensive contrivance in which the parts are coupled together to provide for expansion and contraction under the influence of the heat, but without affecting the slidable connection between the members of the structure.

With these ends in view the invention consists in the peculiar construction and arrangement of parts which will be hereinafter fully described and claimed.

To enable others to understand the invention, I have illustrated the same in the accompanying drawings, forming a part of this specification, and in which—

Figure 1 is a perspective view of my improved adjustable back or lining for fireplaces, the full lines representing the lining in its contracted condition and the dotted lines illustrating said back or lining in its extended position. Fig. 2 is a vertical sectional view on the plane indicated by the line 2 2 of Fig. 3, looking in the direction indicated by the arrow. Fig. 3 is a section at right angles to Fig. 2 on the plane indicated by the dotted line 3 3 of Fig. 2.

Like numerals of reference denote like and corresponding parts in each of the several figures of the drawings.

In the accompanying drawings I have illustrated my improved adjustable lining or back, which is designated in its entirety by the numeral 1. This back or lining consists of the sections 2 3, each of right-angular form to fit the back and sides of a fireplace, and with these sections are combined the adjustable jambs, that are slidably connected to the sides of the sections and are adapted to be moved outward or inward in relation thereto for the purpose of enabling the back or lining to be used in fireplaces of varying depths. The

straight rear parts of the sections 2 3 are arranged to overlap each other, and they are slidably connected together in a manner, 55 presently described, to provide for either expansion or contraction, and thereby enable the back or lining to be used in fireplaces of different widths. The overlapped rear parts of the right-angular sections 2 3 are coupled 60 slidably together in a peculiar manner, which prevents accidental displacement of the sections one on the other and yet provides for their slidable adjustment and for the expansion which may take place in the lining under the 65 heat to which the back or lining is subjected when the fireplace is in use. The section 3 is provided on its front face with parallel ribs or flanges 4 5, which are inclined in opposite directions to each other—that is to say, the flange 70 4 is inclined in an upward direction and the flange 5 in a downward direction. The section 2 is provided on its rear face with parallel grooves or channels 6 7, which are formed therein coincident to the ribs or tongues 4 5 75 and are correspondingly shaped to the cross-sectional contour of said ribs, thus enabling the ribs to fit properly in the grooves or channels and connect the two sections 2 3 together. It will be observed that the ribs or tongues and 80 the grooves or channels are arranged horizontally on the rear parts of the sections 2 3, that they extend longitudinally of said sections, and that the tongues are adapted to interlock loosely in the grooves to connect the sections 85 loosely together, permit of the horizontal adjustment of one or both sections, as may be desired, prevent the accidental disengagement of the sections the one from the other, and provide for the expansion or contraction 90 of the metal under the influence of heat and cold according as the fireplace is used or not.

8 9 designate the adjustable jambs, which are fitted against the outside of the side portions of the sections 2 3, and these jambs are 95 provided at their front edges with the angular flanges 10, adapted to lap against the sides of a fireplace. Each adjustable jamb is attached to one angular section by the interlocking ribs and grooves. The ribs 11 12 are 100 arranged horizontally on the inner face of the lining-section 2 or 3, and said ribs are inclined reversely to each other in a manner similar to the ribs 4 5 on the section 3. Each jamb

has a pair of horizontal parallel grooves 13 14 provided in its face which bears against the side of the lining-section, and said grooves are arranged coincident with the ribs 11 12, 5 and they are shaped to conform to the cross-sectional contour of said ribs. The jamb is thus adapted to be slidably connected to the section against which it is applied, and the peculiar form of joint between the jamb and 10 the lining-section provides for the proper sliding of the jamb on the lining without exposing the parts to accidental displacement and secures the proper coupling of the jamb to the lining under the changing temperatures to 15 which the lining is subjected when in service.

It is well known that a metallic plate of a fireplace will when exposed to heat expand uniformly in opposite directions from a central line of the plate, and in the construction 20 of my fireplace I arrange the ribs on opposite sides of the central line of the sections and incline the upper and lower ribs to extend in opposite directions, as shown in Figs. 2 and 3. This inclination of the horizontal ribs in op- 25 posite directions and their disposition above and below the horizontal center of the sections insure uniformity in the expansion of the ribs when the sections are heated, and as the ribs are fitted loosely in the grooves or channels 30 of the section 3 and jambs 8 9 the parts are joined together, so that they may expand or contract without causing the ribs to become wedged in the grooves or interfering with the adjustment of the sections one upon the other. 35 or the jambs on the sections.

I attach special importance to the employment of the oppositely-facing tapering ribs arranged parallel to each other and horizontally on the lining as well as to the grooves 40 or channels that conform to the cross-sectional shape of the ribs and loosely receive the same in order to couple the parts slidably together. By having the tongues or ribs and the channels taper and incline in op- 45 posite directions the movable parts are prevented from accidental separation. The metal, when expanded under the influence of the heat, does not cause the ribs or tongues to bind tightly in the grooves or channels, 50 and the several parts of the lining or back may be adjusted as desired in fireplaces of

different sizes. It is evident that the sections 2 3 may be drawn outwardly or shoved inwardly to accommodate the back or lining to fireplaces of different widths and that the 55 jambs or either of them may be adjusted horizontally on the sides of the back or lining to properly fit the latter in fireplaces of different depths.

My improved lining is thus adaptable to 60 fireplaces of any ordinary size, and it affords substantial protection to the brickwork or masonry of the fireplace. The improved construction is simple, inexpensive, durable, and readily applied to any ordinary fireplace, and 65 this simple construction recommends the structure to house-owners because of the protection it affords to fireplaces.

It is evident that changes in the form and proportion of parts may be made by a skilled 70 mechanic without departing from the spirit or sacrificing the advantages of the invention.

Having thus described the invention, what I claim is—

The adjustable fireplace-lining comprising the right-angular sections, 2, 3, lapping each other at their inner ends, the upwardly-inclined ribs, 4, 11, arranged at the back and end of the section, 2, and the end of the section, 3, above the horizontal center of the lining, the downwardly-inclined ribs, 5, 12, on the back and end of section, 2, and at the end of section, 3, below the horizontal center of said lining, the inclined grooves in the 85 lapped face of the section, 3, to loosely receive the ribs, 4, 5, and the flanged jambs, 10, overlapping the ends of the sections, 2, 3, and having grooves which receive the ribs, 11, 12, of said sections; all the parts of the lining being 90 slidably united by joints which expand in opposite directions uniformly from the horizontal central line of the lining, substantially as described.

In testimony that I claim the foregoing as 95 my own I have hereto affixed my signature in the presence of two witnesses.

JOHN ALBERT DICKSON.

Witnesses:

FRANK M. BISHOP,
CHAS. A. VETETE.
